UNITED STATES PATENT OFFICE.

GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC SWITCH.

1,081,789.

Specification of Letters Patent. Patented Dec. 16, 1913.

Application filed August 11, 1911. Serial No. 643,582.

To all whom it may concern:

Be it known that I, GEORGE B. THOMAS, a citizen of the United States of America, and residing at Bridgeport, in the county of 5 Fairfield and State of Connecticut, have invented a certain new and Improved Electric Switch, of which the following is a specification.

My invention relates to electric switches 10 and particularly to pull switches, the object of my invention being to provide a simple and efficient operating mechanism therefor, and other features of construction illustrated and hereafter described.

15 In the accompanying drawings Figure 1 is a vertical section through a canopy showing a switch in which my invention is embodied in one form, mounted therein and partially broken away to show certain features of construction; Fig. 2 is a side elevation of the switch operating mechanism and securing bridge, with parts detached and partially broken away; Fig. 3 is a plan of the bridge bushing; Figs. 4 and 5 are respective plan of the blank for and side elevation of the actuating spiral; Fig. 6 is a partially broken away side elevation of the switch with the hickey screw bridge mounted directly on the porcelain body of the switch; 20 Fig. 7 is a side elevation of the switch showing the switch operating mechanism in section and the cover sleeve used when the switch is exposed.

The present switch is particularly designed for canopy work to take the place of the usual pendent switch or the common forms of pull switches now commonly used in canopy fixtures. I have accordingly shown in Fig. 1 the usual canopy 10, the 25 flared upper end of which engages the canopy ring 11 supported by the short conduit sections 12 screwed at their inner ends into the hickey 13. The latter is threaded at 14 to receive the end of the usual wire 30 conduit or other support through which the wires are led into the canopy, passing out through the short conduits 12 to the lamps or other devices in which the switch controlled current is to be used.

50 The switch is here shown as inclosed in a

casing 15 with insulating lining 16, and secured to the hickey by means of a screw 17 passing through the bridge bushing 18 fast with the switch casing 15 and entering the threaded nipple 19 on the lower face of the 55 hickey 13. The switch casing fits over the porcelain body 20 on which the switch is mounted. The switch which may be of any desired character and number of poles is not shown in the drawing since the particular 60 construction thereof, aside from the fact that it is ratchet operated, does not enter into my invention. Wire terminals 21 and 22 for two leading-in wires are shown, with channels 23, 24 in the side of the porcelain 65 for the accommodation of the wires.

The ratchet mechanism of the present switch comprises a ratchet element 25 fast with the switch spindle 26 and the actuating ratchet element 27 fast with the end of the 70 cam sleeve 28. Surrounding the cam slotted sleeve 28 is a second sleeve 29 with straight guide slots 30, and inwardly projecting end flange 31 which engages the end of the cam sleeve 28 and thus prevents the longitudinal 75 displacement thereof while leaving the same free to rotate. A pull rod 32 slides longitudinally within the cam sleeve 28 and is enlarged at its inner end 33 to engage the slide ring 34, on the latter are lugs 35 extending through the cam slots 36 of the sleeve 28 and engaging the guide slots 30 in the sleeve 29. A spring 37 surrounding the pull rod 32, bears against the ring 34 at one 80 end and against the flange 31 on the sleeve 85 29, at the other end. The guide sleeve 29 passes through a bracket 38 carried by the porcelain body and is held against longitudinal displacement by the engagement of the abutment rings 39 and 40 on said sleeve 90 and bracket respectively. The ring 39 on the sleeve is recessed at 41 to receive the offsets 42 of the ring 40 of the bracket, and the sleeve is thus held against rotation. The 95 operation of this ratchet mechanism is readily understood, when the pull rod 32 is drawn outward, it pulls with it the slide ring 34. Inasmuch as the lugs 35 on the latter engage the guide slot 30 of the sleeve 29, they are held against rotation and con- 100

sequently a rotary motion is imparted to the ratchet sleeve 28, through the cam slot 36 of which the lugs 35 pass. This outward movement of the pull rod thus rotates the ratchet element 27 in actuating direction, while the spring 37 which is compressed during the outward movement of the pull rod, serves to automatically return the ratchet sleeve 28 to its normal position. As 10 a simple and inexpensive method of making this ratchet sleeve, I propose to strike a diagonally slotted blank 43 from sheet metal and roll the same to cylindrical form. The tongue 44 and recess 45 at one end of 15 the blank coöperate with the slanting sides of the blank to insure the proper relation of the parts in the completed ratchet sleeve.

Inasmuch as the canopy completely incloses the switch, the necessity for a switch 20 casing does not exist for this style of work and in Fig. 6 I have accordingly shown the switch without the casing 15 and having the bridge bushing 46 secured directly to the porcelain body of the switch by the 25 screws 47 which also hold the bracket 38 in place.

Where the switch is to be exposed I prefer to place a plain cover sleeve 48 over the 30 guide sleeve 29 so as to hide the slot thereof and the mechanism visible therethrough. A pin prick 49 serves to form a thread engaging projection by which the cover sleeve 48 may be screwed on the threads 50 at the outer end of the sleeve 29. When a 35 canopy is employed this thread at the outer end of the guide sleeve 29 is engaged by the nut 51 which holds the ball 52 against the canopy and thus retains the latter in position.

40 The pull rod 32 is bayonet slotted at its lower end to receive a pull member of any suitable character. In the drawing a pull string 53 is illustrated, carrying at its upper end a double ball 54, the smaller end of 45 which enters and engages the bayonet slot of the pull rod.

Various modifications of the structure shown will readily suggest themselves.

I claim as my invention:—

50 1. An electric pull switch having an insulating body, a switch mounted thereon and a ratchet operating mechanism for said switch comprising a ratchet actuating spiral, a longitudinally movable lug engaging said 55 spiral, a sleeve with guide slot for said lug and a bracket on the switch body holding said sleeve against longitudinal and angular displacement.

2. In an electric switch having a ratchet 60 operating mechanism, a tubular actuating spiral, said spiral in blank form comprising a diagonally slotted sheet metal blank having inclined sides and, at one end,

tongue and recess coöperating to form a joint when the blank is rolled to shape, substantially as described. 65

3. An electric canopy pull switch comprising an operating ratchet mechanism, having a fixed guide sleeve threaded at its outer end, a canopy fitting over said switch and a lock nut threaded on said guide sleeve to hold said canopy in position. 70

4. An electric pull switch having an operating ratchet mechanism comprising a spirally slotted sleeve carrying at one end a driving ratchet, a pull rod within said sleeve and having a lug projecting through the spiral slot of the latter, a stationary guide member outside said sleeve and in sliding engagement with said lug on the pull member 80 to prevent rotation of the latter, together with a return spring within the sleeve adapted to be tensioned on the outward movement of the pull rod and serving to automatically return the latter to position 85 after actuation of the switch.

5. An electric pull switch having an operating ratchet mechanism comprising a spirally slotted sleeve carrying at one end a driving ratchet, a pull rod within said 90 sleeve and having a lug projecting through the spiral slot of the latter, a stationary sleeve incasing said ratchet sleeve and vertically slotted to receive and guide the lug on the pull rod to prevent rotation of the latter, together with a return spring surrounding said pull rod and bearing against the head of said stationary guide sleeve, substantially as described. 95

6. An electric pull switch having an operating ratchet mechanism comprising a rotary switch spindle, a ratchet element moving therewith, a coöperating driving ratchet element, a spirally slotted sleeve rotating therewith, a pull member, a fixed guide member and a lug on said pull member passing through the spiral slot of the rotary sleeve and in sliding engagement with said guide member whereby said pull member is held against rotation during the actuation 100 of the switch. 110

7. An electric pull switch having an operating ratchet member comprising a spirally slotted driving ratchet element, a pull member with lug passing through the spiral slot of said driving element, a guide member outside said driving element and slidably engaged by said lug on the pull member, and a bracket mounted on the switch base to hold said guide member against rotation. 115 120

8. An electric pull switch having an operating ratchet member comprising a spirally slotted driving ratchet element, a pull member with lug passing through the spiral slot of said driving element, a guide sleeve 125

surrounding said driving element and slid-
ably engaged by said lug on the pull mem-
ber, a bracket fast on this switch base and
coöperating collars on said bracket and
5 guide sleeve operatively engaged to hold
said guide sleeve against rotation.
In testimony whereof I have signed my

name to this specification, in the presence of
two subscribing witnesses.
